UNITED STATES PATENT OFFICE.

CHARLES E. GERLING, OF BURLINGTON, IOWA.

BODY-KNEADER.

SPECIFICATION forming part of Letters Patent No. 699,916, dated May 13, 1902.

Application filed September 23, 1901. Serial No. 76,275. (No model.)

To all whom it may concern:

Be it known that I, CHARLES E. GERLING, a citizen of the United States, residing at Burlington, in the county of Des Moines and State 5 of Iowa, have invented certain new and useful Improvements in Body-Kneaders; and I do hereby declare the following to be a full, clear, and exact description of the invention, such as will enable others skilled in the art 10 to which it appertains to make and use the same.

This invention relates to improvements in body-kneaders or instruments for massaging purposes, and more particularly to that form 15 of such devices in which is employed means for permitting a free movement of the parts of the device contacting with the body of the person operated upon, whereby the best possible results may be obtained.

20 It consists of certain novel constructions, combinations, and arrangements of parts, as will be hereinafter fully described and claimed.

In the accompanying drawings, Figure 1 25 represents a view in side elevation of a flesh-kneader embodying the features of the present invention. Fig. 2 represents the same in end elevation, parts being broken away to disclose the structure; and Fig. 3 represents 30 an inverted plan view of the block which carries the ball-carrying rods, the said rods being removed. Fig. 4 represents a view similar to Fig. 2 of a slightly-modified construction; and Fig. 5 represents a view in side elevation of a portion of the block carrying the rollers, one of the modified form of rollers being shown.

In the art to which the present invention 35 relates it has been found desirable to provide 40 means for compressing the flesh of the person operated upon and kneading the same in varying degrees of rapidity without an over-amount of friction, and to attain this and other desirable results I provide, as seen in 45 the accompanying drawings, a block of suitable material, as at 1, which is preferably of one piece and is formed with bores, as 2, formed in series longitudinally of the block, the said bores extending inwardly almost to 50 the opposite face of the block. These bores 2 are arranged in transverse pairs and are adapted to receive and retain the ends of rods

3 3, each of which rods is formed with a straight middle portion, as 4, which extends transversely of block 1 and in a parallel plane 55 to that of the lower face thereof. Each of rods 3 is bent inwardly and extends upwardly in a curved line, as at 5, from ends of the straight portion 4, the ends of each of the said rods extending upwardly from said upwardly-curved portions into their respective bores 2. Suitable rollers, as 6, are rotatably mounted upon the straight portions 4 of rods 3, the said curved portions 5 of the said rods conforming to the contour of the contiguous rollers 6.

Any preferred form of handle, as 7, is removably secured to block 1 by having its forward portion, as 8, inserted in an aperture formed in the material of said block.

The operation of the present improved body or flesh kneader will be readily understood by those skilled in the art. The operator grasps handle 7 and strokes the flesh of the person operated upon (usually himself) with 75 the rollers 6, which rotate, thereby lessening the friction and at the same time permitting the depression and kneading of the flesh, whereby the desired increase of circulation of the blood, quickened activity of the nerves, 80 and development of the muscles are attained.

Of course it will be readily apparent that the rollers 6 are mounted upon the straight portion 4 of rod 3 in such manner as not only to be revolvable, but may also have a lateral 85 movement longitudinally of said straight portion, the said rollers being of solid material preferably.

I do not desire to be understood as limiting myself to the precise structure set forth, but 90 shall feel at liberty to deviate therefrom within the spirit and scope of the present invention. For instance, it is not absolutely essential that the portions 5 of rods 3 should be curved; but the block 1 may be made of 95 a suitable size relative to the size of rollers 6 to permit the ends of said rods to be bent directly at right angles to the portion 4 and project straight into the material of said block, as seen in Fig. 4.

The handle 7 is arranged, as above stated, so as to be removable from block 1, whereby the operator may detach the same and grasp the said block itself for operations to be per-

formed upon his body within easy reach of the hands; but if, for instance, that portion of the back above the shoulder-blades is to be operated upon then the said handle is preferably inserted, so that the operation can the more easily be accomplished, the handle facilitating the reach to the otherwise inaccessible parts.

In Figs. 4 and 5 I have illustrated a slightly different form of roller, as 6', which is applied and operated in the same manner as rollers 6, but differs in being formed of elliptical or oval shape and provided in its periphery with notches, as 9, whereby in operation as the said roller or rollers rotate they will produce a pounding action upon the flesh kneaded, while the said notches will have a cupping effect. Of course it will be understood that rollers 6 may be provided with cupping-notches, if desired, and that the peripheries of rollers 6' may be made smooth when preferred.

Having thus described my invention, what I claim as new, and desire to secure by Letters Patent, is—

1. A body-kneader, comprising a block of suitable material, rods projecting therefrom, and elliptical or oval-shaped rollers revolvably

mounted thereon, each of said rollers being comparatively flat in cross-section, substantially as described.

2. A body-kneader, comprising a block of suitable material, rods projecting therefrom, and solid elliptical rollers revolvably mounted thereon, each having its periphery provided with cupping-notches, the said peripheries being of the same material of said rollers, substantially as described.

3. A body-kneader, comprising a block of suitable material, solid elliptical rollers revolvably carried thereby, the peripheries of said rollers being formed of rigid material and each provided with a plurality of cupping-notches, substantially as described.

4. A body-kneader, comprising a block of suitable material, rods projecting therefrom, and solid elliptical rollers revolvably mounted upon said rods and provided with integral rigid peripheries each having a cupping-notch therein, substantially as described.

In testimony whereof I hereunto affix my signature in presence of two witnesses.

CHARLES E. GERLING.
